UNITED STATES PATENT OFFICE.

FRIEDRICH CLEMENS KAUBISCH, OF FREITAL-ZAUKERODE, GERMANY, ASSIGNOR TO
"UNIVERSELLE" CIGARETTENMASCHINENFABRIK J. C. MÜLLER & CO., OF DRESDEN-A, GERMANY.

CIGARETTE MACHINE.

Application filed November 6, 1924. Serial No. 748,134.

To all whom it may concern:

Be it known that I, FRIEDRICH CLEMENS KAUBISCH, citizen of Germany, residing at Freital-Zaukerode, in the State of Saxony, and Republic of Germany, have invented certain new and useful Improvements in and Connected with Cigarette Machines, of which the following is a specification.

The invention relates exclusively to those cigarette tube machines in which a continuous tube rod is formed which is fed forward uninterruptedly. In such machines it has hitherto been usual to reciprocate in the longitudinal direction of the rod the sheath on which the cigarette tube—severed from the rod—is placed. The sheath was first moved towards the rod, which travelled to meet it, and passed into the end of the rod. At the same time the cigarette tube was severed from the rod by cutting means which was also reciprocated in the direction of the rod, and during the cutting operation moved with the speed of the rod in the direction of feed. The sheath was then retracted with the tube thereon at a considerably higher velocity than that of the feed of the rod. On the return movement the mouthpiece coil was inserted and the tube with the coil introduced stripped from the sheath or beak. It is clear that with this known arrangement the sheath or beak must reciprocate in a path of considerable length, which will vary with the variable length of cigarette. In consequence the sheath and the parts carrying it must be moved over an extended path and over part of such path at a very high speed, which in modern high-speed machines has led to unacceptable conditions as regards the movement of masses and the stresses on the operating devices.

It is also clear that in the earlier arrangements of the tube rod, a considerable length of the rod between the point where it leaves the means for closing the rod and supporting it, and the point at which it engages with the sheath, must be left without support. It must be remembered that severing means must be interposed which must move to and fro and which would not permit of the provision within the region of its movement of a stationary guide tube or the like.

Moreover, the sheath reciprocates to and fro and cannot be arranged nearer the severing device than the dimensions of the cigarette tube will permit. In consequence the

free end of the tube rod is deflected by external influences as, for instance, by a draught of air, from its path and consequently does not exactly fit over the sheath which is reciprocated in the direction of the central axis of the rod. As a result waste cigarettes are produced and the operation of the machine is disturbed.

In accordance with the present invention the cigarette tube severed from the rod first passes between pairs of profiled rollers, which rotate about stationary axes, which rollers frictionally engage and feed the tube forward. The pair of rollers run at such a speed that the tube is separated from the rod and is fed forward to the sheath at a speed considerably in excess of that of the rod.

The sheath, therefore, now need be moved only to a slight extent so that the movement of masses is reduced and the operating means not excessively stressed. Further, the cigarette tube may be completely slipped over the sheath so that the distance between the means for stripping the tube from the sheath and the sheath itself may be quite small. The shock produced on the stripper contacting with the tube is thus reduced so that damage to the tube end, hitherto usual, is avoided. In addition, the free end of the tube rod is supported by the feeding rolls and a stationary guide tube or the like may be interposed between the severing device and the feeding rollers for supporting the end of the rod.

The new machine is illustrated in the accompanying drawing which shows the parts necessary for an understanding of the invention.

Figs. 1 and 2 being side views with the rod in different positions, while

Fig. 3 is a front elevation of the feeding rollers.

As shown, the cigarette tube rod *a* is moved continuously forward in the direction of the arrow. It passes between the open shanks *b*, *c*, of the severing device and into the stationary guide tube *d*, the opening of which is widened and slightly rounded off so as to receive smoothly the end of the rod. Thereafter the rod passes between the pair of profiled rollers *e*, *f*, and then between a second pair *g*, *h*. The rollers are mounted in the wall *A* of the frame and carry adjacent the wall driving pinions *i*, the pinions

of the associated profile rollers being in mesh. The upper pinions *i* are driven by a common spur wheel *k*, on the axis of which is mounted pulley *l* which is driven from a 5 pulley *m* on the driving shaft *n* by a belt *m'*. As soon as the forward end of the tube rod *a* passes into engagement with the first pair of rollers *e*, *f*, the cigarette tube *o* is severed from the rod by the severing device and 10 moved during the severing operation with the speed of the rod in the direction of feed. The pairs of rollers *e*, *f*, and *g*, *h*, are driven in such manner that they feed the cigarette tube *o* forward at a speed considerably exceeding that of the cigarette rod. 15

The tube *o* fed forward by the pair of rollers is given up to the sheath *p*, which reciprocates in the direction of the axis of the tube or of the cigarette tube rod. As the 20 work of separating the tube from the rod and the increased movement is already provided for by the pair of rollers, the movement of the sheath may be considerably shorter than heretofore.

25 I claim—

1. In a cigarette tube forming machine, the combination with a continuous cigarette tube fed with constant speed, the severing device and a sheath for facilitating the 30 passing of a mouthpiece into the severed cigarette tube section, of guide members interposed between said severing means and sheath and adapted to feed the severed tube section with greater speed toward said 35 sheath than the speed of the continuous tube, for the purpose specified.

2. In a cigarette tube forming machine, the combination with a continuous ciga-

rette tube fed with constant speed, the severing device and a sheath for facilitating the 40 passing of a mouthpiece into the severed cigarette tube section, of rotary guide members interposed between said severing means and sheath and adapted to feed the severed tube section with greater speed toward said 45 sheath than the speed of the continuous tube, for the purpose specified.

3. In a cigarette tube forming machine, the combination with a continuous cigarette tube fed with constant speed, the severing 50 device and a sheath for facilitating the passing of a mouthpiece into the severed cigarette tube section, of two pairs of grooved rotary feed rollers having stationary axes and interposed between said severing means 55 and sheath and adapted to feed the severed tube section with greater speed toward said sheath than the speed of the continuous tube, for the purpose specified.

4. In a cigarette tube forming machine, the combination with a continuous cigarette tube fed with constant speed, the severing device and a sheath for facilitating the passing of a mouthpiece into the severed cigarette tube section, of two pairs of 60 grooved rotary feed rollers having stationary axes and interposed between said severing means and sheath and adapted to feed the severed tube section with greater speed toward said 65 sheath than the speed of the continuous tube, and a stationary guide between said severing means and said feed rollers, for the purpose specified.

In testimony whereof I affix my signature.

FRIEDRICH CLEMENS KAUBISCH.
